UNITED STATES PATENT OFFICE.

ANTON MAE, OF NEW HAVEN, CONNECTICUT.

PLIERS.

1,313,399.

Specification of Letters Patent. Patented Aug. 19, 1919.

Application filed October 2, 1917. Serial No. 194,332.

To all whom it may concern:

Be it known that I, ANTON MAE, a citizen of the United States, residing at New Haven, in the county of New Haven and State of Connecticut, have invented certain new and useful Improvements in Pliers, of which the following is a specification.

This invention relates to pliers and it is the principal object of the invention to provide pliers having the jaws thereof so arranged as to move in planes parallel to each other at all times, thus permitting an article arranged therebetween to be firmly and positively engaged by the same.

Among other aims and objects of the invention may be recited, the provision of a device of the character mentioned with a view to compactness, and in which the number of parts are few, the construction simple, the cost of production small, and efficiency and operation high.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the same.

In the drawings:

Figure 1 is a side elevation of the improved pliers;

Fig. 2 is a vertical transverse section therethrough;

Fig. 3 is a detail in perspective of one of the jaws of the same; and

Fig. 4 is a fragmentary detail in perspective showing the jaw engaging arms of the crossed handles.

Having more particular reference to the drawings and in connection with which like reference characters will refer to corresponding parts, 1 and 2 represent the crossed handles of the plier construction, the same being bifurcated and pivotally connected as at 3. The bifurcations provide arms 4 upon the ends of said handles, the said arms being offset intermediate of their ends as at 5, as

clearly shown in the Fig. 4. Openings 6 are formed in the outer ends of the arms 4 and 50 serve as means for permitting pivotal engagement of the jaws of the pliers, herein-after referred to.

Located within the bifurcations formed by the arms 4 are jaws 7 and 8, the same being provided with rigid guide arms 9 integral therewith and extended substantially at right angles from these guards, the guide arms 9 being receivable in guide openings or slots 10 formed in the opposite jaws transversely thereof. Obviously, by providing the guide arms 9 and the openings 10, movement of the jaws 7 and 8 to and from each other will be such as to maintain the same in planes parallel to each other at all times. 65 Therefore, an article arranged between the jaws will be firmly and positively gripped thereby. If desired, the engaging portions of the said jaws 7 and 8 may be serrated as at 11. Transversely disposed openings are 70 formed in the jaws 7 and 8 and receive pivot pins 12 therethrough, which pivot pins have the opposite extremities of the same arranged in the bearing openings 6 formed in the outer ends of the arms 4. By so engaging the arms 4 with the jaws 7 and 8, the same may be moved to and from each other by moving the crossed handles 1 and 2 in the desired direction.

Manifestly, the construction shown is capable of considerable modification and such modification as is within the scope of my claim, I consider within the spirit of my invention.

I claim:

In pliers, the combination of a pair of crossed, pivotally connected, bifurcated arms, and jaw pivotally mounted in each bifurcation, each jaw having a transverse guide opening through it, and a rigid arm 90 at one side thereof projecting into the guide opening in the other jaw.

In testimony whereof, I affix my signature hereto.

ANTON MAE.
